SWEET CORN PICKER

George H. Wohlers and Alvin J. Schloesser, Le Center,
Minn., assignors to Wohlers Implement and Mfg., Inc.,
Le Center, Minn., a corporation of Minnesota

Filed June 4, 1968, Ser. No. 12,209

Term of patent 14 years

Int. Cl. D15—03

U.S. Cl. D40—1

FIG. 2

FIG. 3

FIGURE 1 is a side elevational view of the sweet corn picker design;

FIGURE 2 is a side elevational view of the design taken from the side opposite that of FIGURE 1; and

FIGURE 3 is a plan view of the design oriented with FIGURE 1;

FIGURE 4 is a rear view of the design shown in FIGURE 1;

FIGURE 5 is a perspective view showing the front and side of the design;

FIGURE 6 is a front elevational view of the design; and

FIGURE 7 is a perspective view showing the rear and side of the design, and being taken from the diametrically opposite end from FIGURE 5.

The dominant features reside in the solid line portions.

Broken lines have been omitted in FIGURES 5 and 7 for clarity.

We claim:

The ornamental design for a sweet corn picker, substantially as shown and described.
